COMBINATION SECTIONAL BOX SPRING
AND MATTRESS

John Drexler and Alex Benesik, Detroit, Mich.,
assignors of one-third to George Barnes, De-
troit, Mich.

Application March 18, 1935, Serial No. 11,715

1 Claim. (Cl. 5—352)

This invention relates to a combination box spring and mattress and has as its object to provide such a box spring and mattress combination consisting preferably of two or more identical sections to be arranged and rearranged as found desirable.

A further object of the invention is to provide a mattress section capable of being exchanged as found desirable so that the mattress section will maintain its shape and form and always be in fit condition for accommodating the human body.

A further object of the invention is to provide a mattress portion having like coil springs thoroughly protected and covered with cotton or hair so as to provide a mattress that will tend to beneficial relaxation of the user.

Other objects and advantages of the invention will become apparent from the study of the following description taken in connection with the accompanying drawings wherein:

Figure 1 is a top plan view of the combination box spring and mattress with the sections connected together.

Figure 2 is a side elevational view thereof.

Figure 3 is a detail view taken substantially on the line 3—3 of Figure 1.

Figure 4 is an edge elevational view of a tray forming part of the device and

Figure 5 is a fragmentary top plan view of the tray.

Referring to the drawings by reference numerals it will be seen that the combination box spring and mattress comprises preferably two or more, in the illustrated form, three identically constructed sections each indicated generally by the reference numeral 10.

Each section 10 includes a spring structure indicated generally by the reference numeral 11 and a mattress 12.

The spring 11 comprises a tray 13 consisting of flat end pieces 14 connected by flat cross members 15. Opposed side members 16 are also provided and to the upper edges of the side members 16 are secured in any suitable manner, laterally extending flange strips 17. At the corners thereof there are provided substantially Z-shaped brace plates 18 secured to the edges of the pieces 14, 16 and 17, as best shown in Figures 4 and 5. Secured in the bottom of the frame or tray 13 is a sheet 19 of webbing, and upon this sheet 19 rests a plurality of conventional coil springs 20, the endmost series of springs 20 resting on the side flanges 17 as shown in Figure 3. The upper ends of the springs 20 are also covered by an additional sheet 21 of webbing, and placed on the

sheet 21 is a layer 22 of cotton, hair or other suitable filler or stuffing material. Outer covering 23 of suitable fabric is placed over the filler 22, so as to extend downwardly at all four sides of the spring 11 and at its marginal edge is secured to the frame 13 by tacks or other suitable fastening means 24.

Adjacent the marginal edge of the spring 11 the filler 22 in the top of the spring is of reduced thickness so as to provide a clearance or space 10 25 at said marginal edges between the spring 11 and the mattress 12.

As shown in Figure 3, the mattress 12 is disposed upon and supported by the spring 11. The mattress 12 consists of an outer casing or shell 15 26 of any suitable fabric in which are suitably arranged spring pockets 27 surrounded by a filler 28 of cotton, hair or other suitable material. As suggested in Figure 3, the bottom and side walls of the casing 26 are preferably formed from a single sheet of material stitched at its marginal edges as at 29 to a top sheet or covering for the said mattress casing 26.

The mattress 12 may be secured to the spring 11 in any suitable manner as by stitching represented at 12' to retain these two members against relative displacement or if desired, these members may remain mutually separated.

Separable fastener devices, and preferably such fastener devices of the type now generally known in the trade as "zipper" fasteners may be resorted to for detachably connecting the sections 10 together. Such fastening devices are herein illustrated and indicated generally by the reference numeral 30. Preferably, the mattress portion 12 of each section is equipped at each of two opposite sides thereof for such a fastener 30 so that the sections may be interchanged and relatively arranged as found desirable.

From the above it will be apparent that the sections 10 may be arranged as shown in Figure 1 and through the slide fasteners 30 detachably connected together in alignment and in this manner be placed within or supported by the frame of a bed or similar article of furniture. It will be further noted that the clearance spaces 25 may have the marginal edge portions of the sheet or other bed clothing tucked therein.

On the side members 16 there are provided rubber tipped or headed studs or screws 31 adjustable for maintaining a proper clearance between the frames 13 and the rails of the bed frame.

Each spring section is also provided with suitably arranged handle loops 32 secured thereto in

any suitable manner and as shown in Figure 3, and these loops will facilitate the handling of the mattress sections.

While there is herein illustrated and described 5 the preferred embodiment of the invention, it is to be understood that structural changes may be made therein as fall within the scope of the appended claim.

Having thus described the invention, what is 10 claimed as new is:

In a combination spring and mattress assembly, an intermediate unit, and a pair of end units disposed side by side, each unit comprising a lower

spring section and an upper mattress section secured on said spring section, opposite upper side edges and the corner edges of the mattress sections being provided with slide fastener elements for detachably and interchangeably securing said units together, the lower and upper sections of each unit being spaced apart at their ends and sides to provide clothes tucking spaces therebetween mating horizontally and extending completely around the assembly in any inter- 10 changed position of the units.

JOHN DREXLER.
ALEX BENCSIK.
